[57] CLAIM

The ornamental design for a restraining safety swing
seat, as shown and described.

DESCRIPTION

FIG. 1 is a front elevational view of a restraining safety
swing seat showing my new design;

FIG. 2 is a rear view thereof;

FIG. 3 is a bottom view thereof;

FIG. 4 is a side (either) view thereof; and

FIG. 5 is a top view thereof.

The support chain in FIGS. 1, 2 and 4 are shown frag-
mented to indicate indeterminate length.

FIG. 5
